DESIGN.

H. HEATH.
Shirts.

No. 7,782.

Patented Sept. 29, 1874.

UNITED STATES PATENT OFFICE.

HENRY HEATH, OF BROOKLYN, NEW YORK.

DESIGN FOR SHIRTS.

Specification forming part of Design No. 7,782, dated September 29, 1874; application filed September 4, 1874.
[Term of Patent 14 years.]

To all whom it may concern:

Be it known that I, HENRY HEATH, of Brooklyn, of county of Kings and State of New York, have invented or produced a Design for Shirts, of which the following is a specification:

The nature of my design is fully represented in the accompanying photographic illustration, to which reference is made.

A represents the bosom of the shirt, B the collar thereof, and C C the cuffs of the sleeves thereof, these parts comprising the portions of a shirt which are exposed to view by the wearer, and to which my design applies. These parts are made with a ground or face, d, of one color, (solid white being preferred for this purpose,) and with a pattern lining, e, of a different ornamental color—striped blue, for example; the said pattern lining being turned as a border over the white face, so that the latter forms a ground for the effective display of the colored pattern by contrast.

The effect of this contrasted combination is highly pleasing to the eye, and while the compound design presents the glossy appearance of a shirt of pure white, it is more ornamental than the latter, and is highly useful, because it maintains a clean appearance for a longer period, as the parts which come in contact with the skin of the wearer may be of a color that does not show soiling.

I prefer to make the face or ground color white, and the pattern or bordering color blue; but I do not consider the colors selected to be an essential element of my design.

I do not claim a design for a shirt having duplex collars and cuffs, one portion only of each of which is exposed to view at one time; nor do I claim a design produced by such duplication of the acting portions of the cuffs and collar of shirts.

What I claim my invention is—

The design for shirts, hereinbefore described, with cuffs and collar, or either alone, of the ordinary construction, the outer and inner faces of the collar and cuffs, either or both, presenting different colors to view at the same time, one face constituting a ground for the display of the other face, substantially as and for the purpose set forth.

Witness my hand this 3d day of September, A. D. 1874.

HENRY HEATH.

Witnesses:

R. L. HAYWARD,
JOSEPH BIRD.